PORTABLE BOWLING ALLEY

James R. Johnsen and Axel Olfert, Chicago, Ill.

Application April 27, 1931, Serial No. 533,090

7 Claims. (Cl. 273—51)

This invention relates to improvements in portable bowling alleys and it consists of the matters hereinafter described and more particularly pointed out in the appended claims.

5 The primary object of the invention is to provide a portable bowling alley which may be set up for use and taken apart or knocked down for storage, without the aid of tools of any kind, the various parts being so formed and interfitted that 16 they lock together in place to form a rigid, level alley upon which the game may be played with satisfaction.

A further object of the invention is to provide an alley of this kind, including a pit and a gutter 15 which also serves as a ball return, the latter being made in sections as is the bed of the alley and to which it may be easily and quickly attached and detached.

Still another object of the invention is to provide in an alley of this kind, a pit construction 20 which is yieldingly connected to the alley to reduce the impact of the ball and pins so that the back-stop thereof has a greater period of usefulness and the noise and clatter of the ball and pins is reduced to such an extent as to be unobjectionable.

These objects of the invention as well as others, together with the many advantages thereof, will 25 more fully appear as we proceed with our specification.

In the drawings:—

Fig. 1 is a top plan view of a portable bowling alley embodying our invention, in set-up form.

Fig. 2 is a view in side elevation of the same 35 as viewed from the left-hand side of the alley and shows one of the gutters formed to provide a ball return.

Fig. 3 is a top plan view on an enlarged scale, of the pit end of the alley, in its set-up condition, 40 with parts broken away to more fully illustrate the construction thereof.

Fig. 4 is a top plan view on the scale of Fig. 3 of the ball delivery or "foul line" end of the alley.

Fig. 5 is a view in elevation of that end of 45 the alley shown in Fig. 4.

Fig. 6 is a transverse vertical sectional view through a part of the alley toward the pit end thereof, as taken on the line 6—6 of Fig. 3.

Fig. 7 is a perspective view of one of the gutter 50 sections in its folded condition.

Fig. 8 is a perspective view of a certain connecting clip or bracket embodied in one of the gutter sections of our improved alley.

Fig. 9 is a perspective view of another connecting clip embodied in one of the gutter sections of 55

our improved alley and which clip is adapted for cooperation with the clip or bracket shown in Fig. 8.

Fig. 10 is a detail longitudinal vertical sectional view through the abutting ends of the two alley sections with the combined locking bar and supporting beam in the position it occupies before it is turned to extend transversely to draw and lock said alley section ends together.

Fig. 11 is a view similar to that shown in Fig. 10 with the locking bar and supporting beam in a position locking said alley section ends in a drawn together position.

Fig. 12 is a detail horizontal sectional view on an enlarged scale through the alley section locking means as taken on the line 12—12 of Fig. 11.

Fig. 13 is a bottom plan view of one of the intermediate alley sections on the scale of Figs. 3 and 4.

Fig. 14 is a detail horizontal sectional view similar to Fig. 12 and illustrates more particularly the arrangement of the openings in the alley section connecting yokes.

Fig. 15 is a plan view of one end of one of the supporting beams and locking bars employed in our improved alley construction and illustrates more particularly the engagement of the gutter brackets or clips therewith.

In general, our improved alley comprises a plurality of alley sections, namely, a pit and pin end section, a ball delivery or "foul line" section and a number of intermediate sections. Said sections, each of which includes a ball-way or deck, are adapted to abut, end to end and associated with such ends of adjacent sections are members operable to draw said ends tightly together and thereafter lock them in this position, said members thereafter forming the transverse supporting beams or members for the alley. When said members are in this position, they extend laterally beyond each side of said sections so as to there operatively support a sectional gutter and one of said gutters is employed as a ball return. For this purpose that section of said one of said gutters, at the ball delivery end of the alley, is inclined downwardly to form a ball stop.

Associated with the first mentioned alley section is a pit into which the pins fall upon being engaged by the bowled ball. This pit includes side boards or walls and a cross wall, detachably connected together and yieldingly connected as a whole to the associated alley section. The cross wall which carries an impact cushion or pad is provided with floor engaging rollers so that upon impact from the bowled ball, the pit yields rear-

wardly to return to normal position, ready for the next ball to be bowled.

Referring now in detail to that embodiment of the invention, illustrated in the accompanying drawings, our improved alley consists of a pit or pin end section 1, at the "front" end of the alley, a ball delivery or "foul line" section 2 at the "rear" of the alley, and intermediate sections 3, 4 and 5 respectively. The words "front" and "rear" are used only for convenience of expression and with respect to the direction in which a bowler faces the alley when delivering a ball upon the alley.

As the constructions of the various alley sections are substantially alike, a description of one will suffice for all. As best shown in Fig. 13 which illustrates a bottom plan view of one of the intermediate alley sections, the same comprises longitudinally extending side stringers or sills 4^a and similar intermediate stringers or sills 5^a spaced a suitable distance apart and connected at their ends by transverse front and rear end members 6 and 7 respectively and by intermediate transverse brackets 8—8. At each end of each section and following about the various sills and associated cross members and secured thereto in any suitable manner, are pairs of metallic strips 9—9 as best shown in Fig. 13 whereby a strong rigid frame is provided for each alley section.

To such a frame for each section there is secured on the top thereof, a deck or ball-way 10 in the form of flooring-like boards. The end members 6 and 7 are oppositely rabbeted as at 11 (see Fig. 10) so as to better interengage each other and the tongue 12 of each cross member is angled off at the sides as at 13 in Fig. 13 to engage in the like angled off end 14 of the groove 15 of the other end of an abutting section. By this angled off arrangement of the tongues and grooves of the rabbeted connection of the said cross members, the various sections become self-centering or self-aligning and a good even deck or ball-way is assured wherein the cross seams are reduced to such a minimum as to in no manner cause a bowled ball to deviate from its course.

Each cross member 6 and 7 has secured to the center of its bottom surface, horizontally disposed U-shaped, metallic brackets 16 and 17 respectively. These brackets are made of flat metallic stock and the free ends of the bottom arms thereof are adapted to overlap. In the overlapping parts of said arms, are provided oppositely facing key-hole or figure 8-like openings 18 for engagement by certain locking cams as will soon appear. These openings 18 extend transversely of said brackets as best shown in Fig. 14 and when the bracket arms are first engaged, a part of the opening in one arm is offset slightly, with respect to an associated part of the like opening in the other arm as appears in said Fig. 14.

To draw and lock the abutting ends of the sections together as well as to provide transverse support for said ends, I provide a beam-like member 19 of a length somewhat greater than the width of any one of the several sections. Each beam-like member is made up of a pair of laterally spaced, edgewise disposed boards 19^a—19^a secured together in parallel relation by a plurality of rectangular, strap-like brackets 20 and 21 there being a bracket 20 at the middle of said member and a bracket 21 at each end thereof. In the top part of the middle or center bracket is secured an upright stud 22, including top and bottom oppositely facing cams 23, that part of the stud between said cams being of an

elliptical instead of a circular cross section. Said stud is adapted for insertion up through the opposite facing key-hole-like openings 18 in the associated U-shaped brackets 16 and 17 respectively when said openings are in substantially the relation shown in Fig. 14. In the top part of each end bracket 21, of those supporting beams at each end of the alley, is formed an opening 24 best shown in the upper right-hand corner of Fig. 3 and in the bottom left-hand corner of Fig. 4 and the purposes of which will later appear. In the end brackets 21 of each of the intermediate beams 19 is formed an opening 24^b into which opens a recess 24^b extending longitudinally of the beam.

In assembling the alley sections together, they are preferably stood upright upon their sides to expose the overlapping ends of the members 16 and 17. A beam or cross member is then taken in hand and cam 23 of the stud 22 thereof, is then inserted through the registering openings 18 in said members 16 and 17, to bring said cams upon opposite sides of said members. The beam is then turned about the stud 22 as an axis so as to extend transversely of the sections and lines up with the meeting ends thereof. In this turning movement of the beam, the stud 22 so operates against parts of the openings 18 as to not only snugly draw the brackets 16 and 17 and associated alley ends together longitudinally, but the cams 23—23 act to draw said brackets together in the plane of the axis of said stud 22. This drawing together of the brackets in this last mentioned direction, also acts to more tightly engage the rabbeted end members 6 and 7 together in the plane of said axis of the stud to insure a perfect connection between the alley section ends.

When the beams are thus disposed, their ends project beyond the sides of the alley sections so that the various openings as mentioned, in the end brackets 21 of each beam are exposed. When the various sections are secured together by the beams, they are placed upon the floor or other support, with the cross beams down and with the deck or ball-way, of the several connected together sections, uppermost. In connecting the several sections together, it is pointed out that it is more convenient to begin assembly from the pit end and work rearwardly, the pit or front section having the usual spots for the pins as best shown in Fig. 3. While all of the cross beams or supports 19 are substantially alike, that beam associated with the pit end of the pit section is provided on its end brackets with headed studs 25 as best shown in Fig. 3. The brackets 21 for the various cross beams are each provided with leveling or adjusting screws 21^a as best shown in Figs. 1, 5 and 6 respectively.

At the front of the alley is provided the pit indicated as a whole at 26. This pit includes an upright head or cross board 27 and upright side boards 28—28 of a height to extend the desired distance above the bed of the alley. Each side board which is cut away at its rear bottom corner as shown in Fig. 2 is provided on its inner surface near its rear end, with an angle bar strip 29, the horizontal flange 30 of which engages upon the top surface of the end of an associated cross beam 19. In each flange 30, is provided a longitudinal slot 31, having an enlargement 32 at its rear end, of a diameter to permit the head of the associated stud 25 to pass therethrough, after

which said head will then overhang the sides of said slot forward of said enlargement.

Each side board has an outwardly extending hook-like stud 33 to receive one end of a spring 34, the other end of which is adapted for engagement with a similar hook 35 extending outwardly from that beam 19 facing the pit. The front edge of each side board is provided with loops 36 to receive hooks 37 on the ends of the head board whereby the side boards and head board are detachably connected together. The head board is provided at its bottom with suitable rollers 38 for engagement upon the floor or other support upon which the alley is set. Associated with said head board is an impact pad or cushion 39, having hooks for a detachable engagement for the top edge of the head board. During bowling upon the alley, the bowled ball and probably some of the pins will strike the cushion. The impact thereof, will be partially absorbed by the pad or cushion and will also be partially absorbed by the springs 34 in the guided movement of the pit as a whole. If desired a suitable pad or cushion 40 may be employed upon the floor of the pit but this is not absolutely essential.

At each side of the alley bed or ball-way as provided by the various sections, is also provided a gutter, each indicated as a whole by the numerals 41 and 42 respectively, the former being the left-hand gutter and the latter being the right hand gutter. Such gutters are primarily intended for guiding those bowled balls which roll off the alley bed into the pit and one of them; namely, the left-hand gutter in this instance, is used as a ball-return from the pit.

While both gutters are sectional and are of substantially the same construction, one section of the left-hand gutter in this instance; namely, the rearmost section, is pitched downward so that the returned balls are conveniently disposed for use in another bowling. Each gutter is made up of a pit end section 43, a delivery or foul line section 44 and intermediate sections 45, 46 and 47 respectively. In Fig. 7 is illustrated one of the intermediate sections which includes a bottom board 48 and a side guide board 49 hinged together along one edge by longitudinally disposed hinges 50. The straps of said hinges are disposed on the outside of said boards and act to hold the boards in the desired angular relation which is greater than 90° as best shown in Fig. 5. To the front end of each side guide board is pivoted a connecting clip 51, adapted when the sections of the gutters have been set up, to overhang the front end of the guide board of the next gutter section as shown in Figs. 1 and 2. On the front end of the underside of the bottom board of each gutter section is secured a clip or plate 52 (see Fig. 8) having a forwardly extending and slightly offset finger 53. On the rear end of said surface of each bottom board is provided a plate 54 (see Fig. 9) having a depending laterally disposed hook 55.

In assembling the gutter, it is most convenient to start with the gutter section 43. With said section folded together in the condition shown in Fig. 7, the finger 53 on the front end thereof, is inserted into the opening 24 in the bracket 21 of the cross beam 19 at the pit end of the alley. As the gutter sections are each of a length approximating that of the alley bed or ball-way sections, this will bring the hook 55 on the rear end thereof, in line with the opening 24a in the associated bracket 21 of the next cross beam and

into which it is inserted. In applying the rear end of the gutter section in place, said hook is first engaged in said opening 24a and then the rear end of said section is moved laterally inward so that said hook enters the recess 24b to engage the underside of the bracket 21. The side guide board of that particular gutter section just positioned, may now be opened up and its rear end will rest against the associated side board 28 of the pit.

The second gutter section is now grasped while in its folded condition and the finger 53 on the front end thereof, is inserted in the opening 24a of the end bracket 21 of the next or second cross beam 19 and to the outside or rear closed end of the hook 55 on the rear end of the bottom board of the gutter section already in place. This interengaging of the hook and finger mentioned may be readily accomplished by holding the front end of the folded section about to be positioned at a downward and inward angle. After the finger has been engaged in the opening 24 and with the hook 55 as described, the rear end of said folded section is swung in toward the next or third cross beam and its rear end is engaged upon said beam and its hook 55 then lines up with and enters the opening 24a and recess 24b of the third beam. The side guide board of the gutter section just mentioned is then swung into an open position and the clip 51 on its front end is caused to engage the rear end marginal part of the like board of the first positioned gutter section. The gutter sections 46 and 47 are operated upon in the same manner as is the last or rearmost gutter section 44.

This last mentioned gutter section is inclined downwardly towards its rear end and is provided with a pivoted hook 56 the free end of which is engaged in the opening 24a of the end bracket of the last or rearmost cross beam as best shown in Fig. 5. A cushion 57 is then placed in this gutter section, up against said beam to act as a ball-stop for the returned balls. Thus with this section, inclined as mentioned, the balls returned from the pit along said gutter, after a bowl, are retained in position convenient for the bowler in picking up the ball for another bowl. If desired both gutters may be made in this way, but only one is necessary.

The alley, as a whole, may be knocked down for storage, by operations the reverse of those mentioned, and in this respect, several of the folded gutter sections may be placed in between the stringers 4-4 and 5-5 of the various sections. So that the sections may be arranged for storage in but a small space, we provide even numbers of them at diametrically opposite corners on their bottom sides with loops 58-58 to receive studs 59 in the other diametrically opposite corners, as are shown in Fig. 13. Thus two sections may be arranged bottom to bottom with the shorter or smaller parts of the alley as a whole in the spaces between the stringers of the sections, as is apparent.

Our alley as described, may be quickly set up for play without the aid of tools of any kind and may be as quickly knocked down for storage.

When set up, the same provides a true, even, rigid alley upon which bowling may be enjoyed to the utmost. Such a structure is rigidly braced against warping due to temperature changes. Again, such an alley permits enjoyment of the game out in the open such as in the yard of a home or residence and may be adjusted for evenness despite the unevenness of the turf upon which it is set up.

While in describing our invention, we have referred in detail to the form, arrangement and construction of the parts thereof, as well as the manner in which they are assembled, the same is to be considered merely as illustrative, so that we do not wish to be limited thereto except as may be specifically set forth in the appended claims.

5 We claim as our invention:—

- 10 1. In a bowling alley, a plurality of alley sections having meeting ends, each with a cross member thereon, a device on each cross member having a part adapted to overlap a like part in the other device of an adjacent alley section end, said parts having openings therein which register when said parts are so overlapped, a support for said meeting ends adapted to be initially disposed, longitudinally of said sections and then turned transversely thereof, and a double cam member carried by said support and operating through the registering openings in the overlapped parts of said devices on said cross members for drawing and locking said meeting ends tightly together.
- 15 2. In combination with a bowling alley, a support therefor, a gutter along one side of the alley and comprising sections arranged end to end, means on one end of one section for engaging the support upon a lateral movement of said end of said one section and means on the associated end of the other section adapted for engagement with said means on the first section as well as with said support to lock said ends together and to said support.
- 20 3. In combination with a bowling alley, a support therefor, having a part extending to one side of said alley and which part has an opening therein, a gutter along said side of the alley and comprising sections arranged end to end, means in one end of one section adapted for engagement in said opening upon a downward and lateral movement of said end of said section with respect to said support and means on the associated end of the other section adapted for engagement with said means on the first section as well as for engagement in said opening in said support to lock said sections together and to said support.
- 25 4. In combination with a bowling alley comprising a plurality of sections arranged end to end, a supporting member for the meeting end of adjacent sections and extending at one end beyond one side of the alley, a gutter along said side of

the alley and comprising gutter sections arranged end to end, means on the end of one gutter section adapted upon a lateral inward movement of said gutter section end for engagement with said end of said support and means on the associated end of an adjacent gutter section adapted also for engagement with said end of said support for locking both gutter section ends together and to said end of said support.

5. In combination with a bowling alley comprising a plurality of sections arranged end to end, a supporting member for the meeting end of adjacent sections and extending at one end beyond one side of the alley, and which end of said support has an opening therein, a gutter along said side of the alley and comprising gutter sections arranged end to end, means carried on one end of one gutter section adapted upon a lateral movement in one direction upon said end of said support, to be engaged in the opening therein and means on the associated end of the next adjacent gutter section adapted to be entered into said opening to lock both ends of said gutter sections together and to said support.

6. A gutter for a bowling alley including gutter sections arranged end to end, a support for the meeting ends of two adjacent sections and having an opening therein, a laterally extending hook at one end of one of said sections and a longitudinally extending finger on the other end of the other section, said hook and finger being insertable into said opening in said support to secure said meeting ends of said sections thereto.

7. A bowling alley comprising a plurality of alley sections adapted to meet end to end, interengaging cross members on said alley section ends, supporting means for said alley section ends, a cam element on said supporting means, and overlapping devices on said interengaging cross members, said supporting means being adapted to be initially disposed longitudinally of said sections so as to bring said cam element into partial operative engagement with said overlapping devices, said cam upon a turning of the supporting means into a position extending transversely of the alley section ends, operating upon said overlapping devices to draw said alley section ends lengthwise together and to draw said cross members together perpendicularly.
